UNITED STATES PATENT OFFICE.

ARTHUR PESTEL, OF NEW YORK, N. Y.

STRAIN-RELEASING MECHANISM.

Application filed May 21, 1920. Serial No. 383,032.

To all whom it may concern:

Be it known that I, ARTHUR PESTEL, a citizen of the United States, residing at New York, county and State of New York, have invented certain new and useful Improvements in Strain-Releasing Mechanism, of which the following is a full, clear, and exact specification.

This invention relates to improvements in mechanism for releasing strains and is applicable to different forms of mechanism in which release of excessive strains on machine elements is desired.

The object of my invention is to provide mechanism which will eliminate the breaking of taps, drills and other work-performing elements and whereby a device is introduced between power transmitting members, which device will give way whenever the strain on said members does become excessive.

Heretofore it has been customary to provide strain releasing mechanism with drilling and tapping machines or attachments, which mechanism were built into the machine or attachment, and in order to obtain greater or lesser strain-resistance, applicable for larger or smaller sized taps or drills respectively, the operator had to accurately adjust said strain releasing mechanism, which involved more or less mechanical skill and an unnecessary waste of time.

The object of my invention is to provide separate strain releasing units attachable to drilling or tapping machines or the like.

Each unit is made or adjusted to withstand a certain definite strain only and it may be interchanged for other units having a strain resistance of either greater or lesser degrees. My invention is adaptable to different machines and apparatus and can be used in connection with clutches, couplings and the like, but I desire to especially apply the same in connection with tapping and drilling machines.

In carrying out the invention, I also utilize the break-pin shown and described in U. S. Patent Application Ser. No. 357,490, filed February 9th 1920, to which reference may be had.

In the accompanying drawings:—Figs. 1, 2, 3, 4, 5 and 6 show views of a tapholder, such as are used on screw machines and turret lathes and of which Fig. 1 is a front view, Fig. 2 a side view on the line 2—2 Fig. 1, Fig. 3 a plan view on the line 3—3

Fig. 1, Fig. 4 a plan view and Figs. 5 and 6 a detailed plan view and rear view respectively of the breakcollar with the chuck shown in dotted lines, to make the views 60 clearer. Fig. 7 is a view of a breakpin.

Figs. 8, 9, 10, 11, 12, 13, 14 and 15 show views of an other tapholder for screw machines and turret lathes, but of a design different from that shown in Figs. 1, 2, 3, 4, 65 5 and 6.

Fig. 8 shows a sectional side view of the assembled shank and chuck of said tapholder, Fig. 9 is a front view on the line 9—9 Fig. 8. Fig. 10 is a front view of a 70 strain releasing unit attachable to said shank and chuck Fig. 8; Fig. 11 is a side view on the line 11—11 Fig. 10; Fig. 12 is a plan view on the line 12—12 Fig. 10; Fig. 13 is a partial bottom view of Fig. 11; Fig. 75 14 is a detailed modified view of a spring attachment. Fig. 15 is a plan view of the complete tapholder assembled. Fig. 16 is a side view of a wrench and Fig. 17 is a sectional plan view of same on the line 80 17—17 Fig. 16.

Figs. 18, 19, 20, 21, 22, 23 and 24 show views of a strain-releasing unit to be used in connection with high speed drilling attachments, tapping machines and the like. 85

Fig. 18 is a plan view of said unit on the line 18—18 Fig. 19. Fig. 19 is a sectional view on the line 19—19 Fig. 18 and Fig. 20 a sectional view on the line 20—20 Fig. 18.

Fig. 21 shows a sectional view of a high 90 speed drilling attachment connected with said strain releasing unit. Fig. 22 shows a plan view of a plate; Fig. 23 a sectional view of same on the line 23—23 Fig. 22. Fig. 24 is a partial view of a cylinder. 95

Figs. 25, 26, 27, 28 and 29 show views of a chuckholder for drillpresses, lathes and similar machines.

Fig. 25 shows a sectional side view of the collet and head of said chuckholder. Fig. 100 26 is a front view of a strain releasing unit, attachable to said collet and chuck, Fig. 25.

Fig. 27 is a side view on the line 27—27, Fig. 26. Fig. 28 is a rear view of said unit. Fig. 29 is a plan view of the complete chuck- 105 holder assembled.

Referring to Figs. 1, 2, 3, 4, 5, 6 and 7 No. 1 indicates a shank, made to fit into the head of the turret of a screw-machine and to be clamped thereto in any well known 110 manner.

Casing 2, which is fitted to the rim 3 of

shank 1 is fastened to said rim with three screws 4 and one longer screw 5. The break-collar 7, which is rotatable in and between said shank rim 3 and casing 2 on annular bearing surfaces 8 and 9 respectively, has adjacent and concentric to each of said bearing surfaces a breakrim 10 and 11 respectively.

Said breakrims, which are larger in diameter than said bearing surfaces, are cut open on one place at a slight angle as shown on ends 12 and 13, Figs. 3 and 6 and relieved opposite each end approximately one fourth of the circumference of said breakrims as shown at 14 and 15 Fig. 6.

The head or chuck 16, holding a tap 17 by means of two semicircular clampblocks 18, 19 and a screw 20, has a shank 21 which is concentrically and rotatably mounted in breakcollar 7. Said shank, which has a hole 22, has also at its furthest end a groove 23 into which is fitted a flat pin 24, fastened to said shank by means of a rivet or screw 25.

Said pin has on one end an extension 26, long enough to clear a shallow hole 27 in breakcollar 7. Said hole has a depth alike to the thickness of pin 24 at one third the circumference of said hole and the depth alike to the double thickness of pin 24 at the remainder of the circumference.

One step 28, Fig. 5, obtained by means of these different depths is cut at approximately right angle, to allow extension 26 to firmly rest against said step, while the other step 29 is formed on a slant and gradually rises from the lower to the upper surface of hole 27. Bearing surface 8 of breakcollar 7 has two clutch teeth 30 and 31 Figs. 5 and 6 respectively, to engage pins 32, fast in head 16.

Casing 2 has on its circumference a rectangular opening 33 in which are held by means of two screws 5 and 6 two steel guide plates 34. These plates, both of which are alike, have in the middle a triangular groove 35 which is relieved at 36.

When the plates are assembled, grooves 35 will form a rectangular opening, large enough to allow breakpin 37 to pass freely. Breakpin 37, which may be made of any suitable material, has on both sides a row of definitely spaced notches 38, thus dividing said breakpin into a row of links 39.

The length of each link is approximately alike to the height of ends 12 and 13 of breakrims 10 and 11 respectively.

A snappin 40, movable in an extension 41 of casing 2, pressed towards the centre by means of a spring 43, has fast on its other end a knob 44 and engages with its other larger end 45 one of the lowest notches 38 of pin 37, thus preventing said pin from coming out. Casing 2 has an opening or outlet 46 which has the approximate width

of breakpin 37 and serves the purpose to permit the discharge of a broken link 39.

Breakpin 47, Fig. 7, which is a modified view of pin 37, has links 48 formed by slots 49 which at the bottom are V shaped, so as to insure the breaking of said links at this particular point. It is of course understood that the depths of said slots depend on the size of the work performing element, as tap 17.

The operation of said tapholder is as follows: The tapholder which is fastened in the turret head of a screw machine is fed against the work rotating in a chuck of said machine, forcing the tap 17 and head 16 against the breakcollar 7, thus allowing pins 32 to engage the clutch teeth 30 and 31, forcing the breakcollar 7 to rotate in a clockwise direction.

Breakpin 37, held stationary in guide plates 34 and positively engaging breakcollar 7 at the rim ends 12 and 13, prevents said collar from turning, but will yield and break, should the strain on the tap be near its breaking point. In such a case the link 39 thus broken off, will be carried along with the now disengaged breakcollar, until it reaches the opening 46, where it will drop out and allow the breakcollar and therefore the tap 17 to rotate with the work until the machine has been stopped.

In order to again lock said breakcollar, the operator will draw back snappin 40 by means of knob 44 and push in the breakpin until its lower link has again positively engaged the rim-ends 12 and 13 as indicated in Figs. 2 and 3. If however the link has not been broken and the tap has threaded the work its full depth, the rotation of the chuck in the screw-machine is reversed, the turret-head and therefore the tapholder and tap is drawn back. This will disengage pins 32 and bring in engagement extension 26 of pin 24, with the step 28, thus exerting a rotary anticlockwise movement to said breakcollar. The strain in this case is taken up by the rim end 13 which will force link 39 to yield and break should the strain be near the breaking point of the tap.

It will be noticed, that the breakcollar 7 exerts torsional strains to the breakpin 37, which strains force the link 39 to perform a quasi rotary movement before breaking.

It is of course understood, that this tapholder may also be fastened to the chuck spindle of a tapping attachment in a drill-press, in which case the tap would be rotating, while the work to be tapped would remain stationary.

Referring to Figs. 8, 9, 10, 11, 12, 13, 14, 15, 16 and 17, No. 96 is a shank having a rim 97 and an extension 98 with a hole 99. Freely rotatable in said hole is a sleeve 100 with a groove 101 into which fits shoulder screw 50, held in extension 98, preventing

said sleeve from moving in and out of said hole. At each end of sleeve 100 are clutch teeth 51 and 52 for engagement of either pins 53 in head or chuck 54 or pin 55 fast in shank 56 rotatable in sleeve 100.

The strain releasing unit 206 Figs. 10, 11 and 12 has a sleeve 57 with a large inner hole 58 to slide over extension 98 Fig. 8. Flange 59 of said sleeve has three extensions 60 with V-shaped grooves or friction faces 61 in which are resting three posts 62 fast in casing 63 each of said posts having two angular friction faces 207. Casing 63 is slidable and rotatable on sleeve 57 and extensions 60. Said casing and therefore posts 63 are drawn against extensions 60 by means of three springs or pressure elements 64 held to rim 59 by means of pins 65 passing hole 66 and to casing 63 by means of wire ring 67 resting in groove 68. The looped end 69 of each spring 64 passes through clearance hole 86, Fig. 11.

Should it be desirable to make said springs 64 adjustable, adjustment screws 70, Fig. 14 with checknuts 71 may be substituted for wire ring 67, in which case the looped ends 69 of springs 64 would be held in holes 72 at the end of each screw 70.

In the center of casing 63 is a hole 73, Fig. 10, with two tongues 74 and a rectangular shaped opening 75, large enough to admit and positively engage pin 76, fast on sleeve 100, Figs. 8 and 9.

The distance between the extreme end of pin 76 and the center of sleeve 100 is slightly more than the length of the radius of hole 73 incasing 63, in order to force the operator to properly locate pin or engaging element 76 in opening 75 when assembling unit 206 with shank and chuck 77.

The head 78 of shoulder screw 79, Figs. 11 and 13 in extension 60 of sleeve 57 passes through casing 64, which casing at this place has a slot 80, serving the purpose to prevent the same to be turned too far to either the right or left, or to be drawn out, which in these cases might stretch the springs unnecessarily and change the tensions of same.

The three threaded holes 81 in extensions 60 are for the purpose of locking unit 206 to rim 97 by means of screws 82 Fig. 8. Said screws have a shoulder 83 and fast to the ends of shanks 84 knurled knobs 85 to prevent said screws from falling out.

When the shank and chuck 77 and strain releasing unit 206 Fig. 15 are assembled, the operation of said tapholder is similar to the tapholder shown in Figs. 1, 2, 3, 4, 5 and 6 with the difference that if the strain on tap 87 is too great, pin 76 which imparts a strain on casing 63, will force posts 62 out of their positions and turn until they have reached the edges of extensions 60, when

springs 64 will draw casing 63 towards sleeve 57 and thus positively disengage pin 76 from casing 63, allowing sleeve 100 and therefore chuck 54 and tap 87 to rotate freely.

The end of extension 98 is partly relieved 70 at 88, the depth of said relieve being a little more than the thickness of the tongues 74 on casing 63 Fig. 10 and serves the purpose to allow said tongues sufficient clearance when casing 63 is in a released position. 75

To return said casing to an engaged position, it is necessary to partly turn the same and draw it forward until posts 63 have again engaged grooves 61. In some cases the power required to return the casing may 80 necessitate a wrench 89 Figs. 15 and 17. This wrench has on one end a pinhandle 90 and on the other a guide pin 91 which fits in hole 92 Figs. 8 and 9.

The recess 93 in rim 97 is made large 85 enough to allow tongue 94 of wrench 89 to freely pass into same, so that wrench tongue 94 may engage in notch 95 Fig. 15 and by turning said wrench replace casing 63 to an engaged position. 80

It is of course understood, that in order to provide strain releasing units of greater or lesser tensions either stronger or weaker springs may be employed or the angles of friction faces 61 and 207 may either be 95 increased or decreased respectively.

Referring to Figs. 18, 19, 20, 21, 22, 23 and 24 No. 102 indicates a sleeve with a threaded shoulder 103, a rim 104 and two tongues 105 with grooves 106 at their ends. Resting in 100 said grooves and fastened to said tongues by means of two screws 156 is a plate 107 Figs. 22 and 23 which has in its center a threaded hole 108 and at each end a screw hole 157.

Eyescrew 109 held in plate 107 and locked 105 thereto by means of nut 110, has on one end a slot 111 and on the other an eye or hook 112, holding therein looped end 113 of spring or pressure element 114. Cylinder 115 movable in hole 116 of sleeve 102 has 110 resting on recess 117 a washer 118 Fig. 20. Rotatable in the cupshaped hole 119 of said washer is a semiball 120 with a hole 121 and a slot 122 in which rests flattened out end 123 of spring 114. 115

Rim 124 on cylinder 115 has on its lower end a clutch-face 125, on the other end a shoulder 126 and is partly covered by hole 127 in sleeve 102. The upper end of cylinder 115 has two notches 128 Fig. 24, arranged opposite to each other and adjacent thereto two other notches 129, having each a frictionface 208, said notches are however more shallow than notches 128. Resting on said frictionfaces 208 are two angular 125 shaped extensions 130 Figs. 19 and 23 forming part of plate 107 having each a friction face 209 and are drawn against the cylinder

115 by means of spring 114. Said extensions are made circular on their outer edges 131 Fig. 22, so as to fit into hole 116.

Casing 132 has on the inside of its shell 5 133 two tongues 134 the inner ends 135 snugly fitting on cylinder 115.

Two screws 136, with their heads sunk into shell 133, connect and hold together casing 132 and cylinder 115.

10 Rim 104 has a number of holes 137.

In Fig. 21, which indicates a plan view of a high speed drilling attachment, cover 138 which is fastened to casing 139 in any well known manner, has rotatable therein a driv-

15 ing shaft 140 and fast to same a large gear 141, driving a smaller gear 142 rotatable in bearing 143. Shoulder 144 of gear 142 has on the inside a thread 145 into which is screwed a strain releasing unit 146 as shown 20 on a larger scale in Figs. 18, 19, 20, 22, 23 and 24. Clutchface 125 of said unit engages a clutchface or engaging element 148 of clutch member 147 which has a threaded extension 149 screwed into a hollow 25 spindle 150.

Said spindle is rotatable in gear 142 on one end and in casing 139 on the other and has fast to it a large gear 151 which drives a smaller gear 152 fast on chuck spindle 30 153 which in turn is rotatable in a loose bushing 154 in shaft 140 on one end and in casing 139 on the other. Fast to spindle 153 and only partly shown is a chuck 155.

The operation of said strain releasing unit 35 is as follows: The high speed drilling attachment is fastened in the spindle of a drill press, lathe or other suitable machine by means of the driving shaft 140, driving the chuck spindle 153 at a higher speed than that 40 of shaft 140 on account of the different ratio of gears 141, 142, 151 and 152.

Should the strain on a tool fastened in 45 chuck 155 become too great, the hollow spindle 150 and its clutch member 147 which imparts a strain on cylinder 115 Figs. 19 and 20 will eventually force said cylinder to retard its motion until extensions 130 on plate 107 have reached the edges of frictionfaces 208 and 209, when spring 114 will draw 50 up said cylinder and force extensions 130 to engage notches 128, thus positively disengaging the two clutch faces 125 and 148 Fig. 21 and stop hollow spindle 150, gears 151 and 152 and chuck 155 with its tool from 55 rotating.

To return the cylinder from a positively disengaged to an engaged position, the operator stops the machine and pushes down and partly rotates casing 132 until frictionfaces 60 209 have again engaged frictionfaces 208.

To fasten or unscrew said unit to said attachment a pin or pinwrench may be inserted in one of the holes 137 of rim 102 and turned in the direction desired.

65 In order to provide strain releasing units

of greater or lesser tension, either the springs may be varied or the angles of frictionfaces 208 and 209 may be changed.

It is of course understood that this unit may also be applied on tapping attachments 70 similar to the one shown in my United States Patent No. 1,410,717, issued March 28, 1922.

Referring to Figs. 25, 26, 27, and 29, Fig. 25 indicates a collet and chuck 158 of a 75 chuckholder 159 Fig. 29, having a tapered shank 160 made to fit into the spindle of any standard drillpress, milling machine and the like.

Rotatable in hole 161 of said shank is a 80 chuck spindle 162, having fast to its larger end 163 a chuck 164 with a drill 165. The other end 166 of said spindle is rounded and abuts against a steel disk 167 which serves the purpose to take up the thrust imparted 85 from the chuck to said spindle.

Protruding into a groove 168 of spindle 162 is a snap pin 169 with a shoulder 170 to prevent said pin from resting on the bottom of groove 168. This snap pin which 90 is guided in hole 171 of rim 172 is pressed in the direction of chuck-spindle 162 by means of a spiral spring 173. At the other end of said spring in hole 171 is a screw 174 which has a slot 175. Fast to shank 176 of 95 pin 169 is a small plate 177 which has the same width as slot 178 in rim 172.

Near the longer end of said plate in rim 172 is a small notch 179, which serves the purpose to enable the operator to easily 100 grasp plate 177, lift the snap pin and take out chuck spindle 162.

Riveted to rim 172 are two lock pins 180 Fig. 29 with a head 181, small enough to 105 clear holes 182 in threaded sleeve 183 Figs. 27 and 28. To concentric slots 184, 185 have the approximate width of the diameter of pins 180 at the outer surface 186 of said sleeve and an approximate depth of the length of the protruding pins 180. Further back however said slots have the same 110 width as the diameter of holes 182.

Rotatable in sleeve 183 and pressed against shoulder 187 by means of shoulder 188 of adjustment ring 189, is a friction ring 190 115 which has a slot 191. Lockring 192 serves the purpose to lock adjustment ring 189 after the desired pressure on friction ring 190 has been obtained.

Rings 189 and 192 are knurled on their 120 circumferences 193 and have each a number of holes 194 to securely lock said rings with a pin or pin wrench.

Hole 195 of sleeve 183 fits shoulder 196, and the unit 197 may be slipped over chuck 125 164 and attached to collet 158 in the usual well known manner.

Fast to or forming part of the chuck spindle 162 is a rectangular pin or engaging element 198 which engages in the opening 130

199 of friction ring 190. A similar rectangular opening 200 in threaded sleeve 183 serves as a clearance hole to allow pin 198 to pass said sleeve when attaching the unit.

5 In some cases chuck 164 may be larger in diameter than hole 193 in sleeve 183. The operator will then remove chuck and spindle from collet 158 in the way already described, slip on the desired unit 197 and again insert 10 said chuck and spindle.

In operation the chuck spindle 162 and therefore chuck 164 is turned by means of friction ring 190. If the strain on drill 165 is near the breaking point of said drill, friction ring 190 will yield and turn with chuck spindle 162 until the strain has been released from the drill or the machine has been stopped.

It will be noted, that in each one of the 20 various constructions as shown and described, are employed members and elements performing like functions. These members and elements are listed below under separate headings, designating their functions. The 25 names of these headings will be employed in the claims to follow.

Strain inducing members: Figs. 1 to 7 guide plates 34; Figs. 8 and 9 rim 97 with screws 82; Fig. 21 gear 142; Figs. 25 and 29 30 rim 172 with lock pins 180.

Strain releasing unit or units: Figs. 2 and 7 breakpins 37 and 47 respectively; Figs. 10, 11 and 12 unit 206; Fig. 21 unit 146; Figs. 26, 27 and 28 unit 197.

35 Strain receiving members: Fig. 3 complete head 16 with tap 17; Fig. 8 complete head 54 with tap 87; Fig. 21 clutch member 147; Fig. 25 spindle 162.

Strain transmitting elements: Figs. 2 and 40 7 the second engaged link of units 37 and 47 respectively, if the complete tap holder is rotated; Figs. 10, 11 and 12 sleeve 57 of unit 206; Figs. 19 and 20 sleeve 102 of unit 146; Figs. 27 and 28 sleeve 183 of unit 197.

45 Release elements: The lower link of units 37 and 47 of Figs. 2 and 7 respectively, if the complete tap holder is rotated; Figs. 10, 11 and 12 casing 63 of unit 206; Figs. 19 and 24 cylinder 115; Fig. 27 friction ring 50 190 of unit 197.

Having thus described my invention, it is of course understood, that the strain releasing unit 206 Fig. 15 may be used in connection with the collet and chuck shown in Fig. 55 25 and that unit 197 Figs. 26, 27, 28 may be made to be used in connection with shank and chuck 77 Fig. 8.

It is also understood that I do not hold myself to the precise construction of these 60 mechanisms and that I consider myself at liberty to vary the arrangements and constructions of same, without departing from the spirit of my invention.

I claim:

65 1. In mechanism of the character de-

scribed, a strain inducing member, a unit, a strain forming a permanent part of said inducing member, receiving member, a strain transmitting and a release element in said unit, spring means connecting both said elements and means to positively engage said unit with said inducing and said receiving member. 70

2. In mechanism of the character described, a strain inducing member, a unit, 75 a strain receiving member, a strain transmitting and a release element in said unit, spring means connecting both said elements and means to attach and detach said unit to and from one of said members for positive 80 engagement with the other of said members, without dislocating either of said members.

3. In mechanism of the character described, a rotatable strain inducing member, a unit, a rotatable strain receiving 85 member, a strain transmitting and a release element in said unit, spring means connecting both said elements and means to attach and detach said unit to and from one of said members for positive engagement with 90 the other of said members, without dislocating either of said members.

4. In mechanism of the character described, a strain inducing member, a unit, a strain receiving member rotatable in said 95 inducing member forming a permanent part of the latter, means to positively engage said unit with said inducing and said receiving members, elements forming part of said unit to transmit a strain or strains 100 from said inducing member to said receiving member and means to repeatedly set free said strains in said unit.

5. In mechanism of the character described, a strain inducing member, a unit, a strain receiving member rotatable in said 105 inducing member, means to attach and detach said unit to and from one of said members for positive engagement with the other of said members, without dislocating either 110 of said members, said unit to transmit a strain or strains from said inducing member to said receiving member and means to repeatedly set free said strains in said unit.

6. In mechanism of the character described, a strain inducing member, a unit, a strain receiving member rotatable in said inducing member forming a permanent part of the latter, means to positively engage said unit with said inducing and receiving members, elements forming part of said unit to transmit a strain or strains from said inducing member to said receiving member and a release element in said unit to repeatedly set free said strains in said unit. 115

7. In a mechanism of the character described, a strain inducing member, a unit, a strain receiving member rotatable in said inducing member, means to attach and detach said unit to and from one of said members 120 125

for positive engagement with the other of said members, without dislocating either of said members, said unit to transmit a strain or strains from said inducing member to 5 said receiving member and a release element in said unit, to repeatedly set free said strains in said unit.

8. In mechanism of the character described, a strain inducing member, a unit, a 10 strain receiving member rotatable in said inducing member forming a permanent part of the latter, means to positively engage said unit with said inducing and said receiving members, elements forming part of said 15 unit to transmit strains from said inducing member to said receiving member in two different directions and means to repeatedly set free said strains in said unit.

9. In mechanism of the character described, a strain inducing member, a unit, a strain receiving member rotatable in said inducing member forming a permanent part of the latter, means to positively engage said unit with said inducing and said receiving 25 members, elements forming part of said unit to transmit strains from said inducing member to said receiving member in two different directions and a release element in 30 said unit to repeatedly set free said strains in said unit.

10. In mechanism of the character described, a strain inducing member, a unit, a strain receiving member forming a permanent part of said inducing member, means to positively engage said unit with said members, to transmit a strain or strains from said inducing member to said receiving member and further means to repeatedly set free said strains in said unit.

40 11. In mechanism of the character described, a strain inducing member, a unit, a strain receiving member forming a permanent part of said inducing member, means to positively engage said unit with 45 said members, to transmit a torsional strain or strains from said inducing member to said receiving member and further means to repeatedly set free said strains in said unit.

50 12. In mechanism of the character described, a strain inducing member, a unit, a strain receiving member forming a permanent part of said inducing member, means to positively engage said unit with 55 said members, to transmit strains in two different directions from said inducing member to said receiving member and further means to repeatedly set free said strains in said unit.

60 13. In mechanism of the character described, a strain inducing member, a unit, a strain receiving member forming a permanent part of said inducing member, means to positively engage said unit with 65 said members, to transmit a strain or strains

from said inducing member to said receiving member and a release element in said unit, to repeatedly set free said strains in said unit.

14. In mechanism of the character described, a strain inducing member, a unit, a strain receiving member forming a permanent part of said inducing member, means to positively engage said unit with said members, to transmit strains in two different directions from said inducing member to said receiving member and a release element in said unit, to repeatedly set free said strains in said unit.

15. In mechanism of the character described, a strain inducing member, a unit, a strain receiving member, means to attach and detach said unit to and from one of said members for positive engagement with the other of said members, without dislocating either of said members, said unit to transmit a strain or strains from said inducing member to said receiving member and further means to repeatedly set free said strains in said unit.

16. In mechanism of the character described, a strain inducing member, a unit, a strain receiving member, means to attach and detach said unit to and from one of said members for positive engagement with the other of said members, without dislocating either of said members, said unit to transmit a strain or strains from said inducing member to said receiving member and yielding to said strains in said unit.

17. In mechanism of the character described, a strain inducing member, a unit, a strain receiving member, means to attach and detach said unit to and from one of said members for positive engagement with the other of said members, without dislocating either of said members, said unit to transmit strains in two different directions from said inducing member to said receiving member and to repeatedly set free said strains in said unit.

18. In mechanism of the character described, a strain inducing member, a unit, a strain receiving member, means to attach and detach said unit to and from one of said members for positive engagement with the other of said members, without dislocating either of said members, said unit to transmit a strain or strains from said inducing member to said receiving member and a release element in said unit, to repeatedly set free said strains in said unit.

19. In mechanism of the character described, a strain inducing member, a round strain transmitting element, a plurality of extensions on said element, each of said extensions having one or more angular frictionfaces, the total length of said frictionfaces on each of said extensions being a fraction of the total circumference of said

transmitting element, a release element, having like extensions and like frictionfaces thereon, spring means pressing said release element against said transmitting element 5 and in engagement with said frictionfaces, a strain receiving member, an engaging element forming part of said receiving member, means to engage said release element with said engaging element, said release element 10 to permanently disengage from said receiving member after a movement of said transmitting element in either one of two directions and in advance of said release element, the length of said movement being 15 equal to the total length of said frictionfaces and means to return into engagement the frictionfaces of both of said elements.

20. In mechanism of the character described, a strain inducing member, a round strain transmitting element, a plurality of extensions on said element, each of said extensions having one or more angular frictionfaces, the total length of said frictionfaces on each of said extensions being a 25 fraction of the total circumference of said transmitting element, a release element, having like extensions and like frictionfaces thereon, spring means, pressing said release element against said transmitting element 30 and in engagement with said frictionfaces, a strain receiving member, means to engage said release element with said receiving member, said release member to permanently disengage from said receiving member after a movement of said transmitting element 35 in either one of two directions and in advance of said release element, the length of said movement being equal to the total length of said friction faces and means 40 to return into engagement the friction faces of both of said elements.

21. In mechanism of the character described, a strain inducing member, a round strain transmitting element, a plurality of 45 extensions on said element, frictionfaces on said extensions, the length of said frictionfaces on each of said extensions, being a fraction of the total circumference of said transmitting element, a release element having like extensions and frictionfaces thereon, spring means, pressing said release element against said transmitting element and in engagement with said frictionfaces, a strain receiving member, means to engage 50 said release element with said receiving member, said release element to permanently disengage from said receiving member after a movement of said transmitting element in either one of two directions and 55 in advance of said release element, the length of said movement being equal to the length of said friction faces and means to return into engagement the friction faces of both of said elements.

65 22. In mechanism of the character de-

scribed a strain inducing member, a round strain transmitting element, a plurality of extensions on said element, frictionfaces on said extensions, the length of said frictionfaces on each of said extensions being a 70 fraction of the total circumference of said transmitting element, a release element having like extensions and frictionfaces thereon, pressure means, pressing said release element against said transmitting element 75 and in engagement with said frictionfaces, a strain receiving member, means to engage said release element with said receiving member, said release element to permanently disengage from said receiving member after a 80 movement of said transmitting element in either one of two directions and in advance of said release element, the length of said movement being equal to the length of said frictionfaces and means to return into 85 engagement the frictionfaces of both of said elements.

23. In mechanism of the character described a strain inducing member, a strain transmitting element, a plurality of extensions on said element, each of said extensions having one or more angular frictionfaces, a release element having like extensions and like frictionfaces thereon, spring means pressing said release element against said transmitting element and in engagement with said frictionfaces, a strain receiving member, an engaging element forming part of said receiving member, means to engage said release element with said engaging element, said 95 release element to permanently disengage from said receiving member after a movement of said transmitting element in either one of two directions and in advance of said release element and means to return 100 into engagement the frictionfaces of both of said elements.

24. In mechanism of the character described a strain inducing member, a strain transmitting element, a plurality of extensions of said element, each of said extensions having one or more angular frictionfaces, a release element having like extensions and like frictionfaces thereon, pressure means pressing said release element against transmitting element and in engagement with said frictionfaces, a strain receiving member, an engaging element forming part of said receiving member, means to engage said release element with said engaging element, said 110 release element to permanently disengage from said receiving member after a movement of said transmitting element in either one of two directions and in advance of said release element and means to return into 115 engagement the frictionfaces of both of said elements.

25. In mechanism of the character described a strain inducing member, a strain transmitting element, a plurality of exten-

sions on said element each of said extensions having one or more angular frictionfaces, a release element having like extensions and like frictionfaces thereon, pressure means 5 pressing said release element against said transmitting element and in engagement with said frictionfaces, a strain receiving member means to engage said release member with said receiving member said release 10 element to permanently disengage from said receiving member after a movement of said transmitting element in either one of two directions and in advance of said release element and means to return into engagement the frictionfaces of both of said elements.

26. In mechanism of the character described a strain inducing member, a strain transmitting element, a plurality of extensions on said element frictionfaces on said 20 extensions, a release element having like extensions and frictionfaces thereon, spring means pressing said release element against said transmitting element and in engagement with said frictionfaces a strain receiving member, an engaging element, forming part of said receiving member, means to engage said release element with said engaging element, said release element to permanently disengage from said receiving member after 30 a movement of said transmitting element in either one of two directions and in advance of said release element and means to return into engagement the frictionfaces of both of said elements.

35. 27. In mechanism of the character described a strain inducing member, a strain transmitting element, a plurality of extensions on said element frictionfaces on said extensions, a release element having like 40 extensions and frictionfaces thereon, pressure means, pressing said release element against said transmitting element and in engagement with said frictionfaces, a strain receiving member, an engaging element forming part of said receiving member, means to engage said release member with said engaging element, said release element to permanently disengage from said receiving member after a movement of said 45 transmitting element in either one of two directions and in advance of said release element and means to return into engagement the frictionfaces of both of said elements.

55. 28. In mechanism of the character described a strain inducing member, a strain transmitting element, angular frictionfaces thereon, a release element with like frictionfaces, spring means pressing said release element against said transmitting element 60 and in engagement with said friction faces, a strain receiving member, means to engage said release element with said receiving members, said release element to permanently disengage from said receiving member after a movement of said transmitting 65

element in either one of two directions and in advance of said release element and means to return into engagement the frictionfaces of both of said elements.

29. In mechanism of the character de- 70 scribed a strain inducing member, a strain transmitting element, angular frictionfaces thereon, a release element with like frictionfaces, pressure means, pressing said release element against said transmitting element and in engagement with said frictionfaces, a strain receiving member, means to engage said release element with said receiving member, said release element to permanently disengage from said receiving mem- 75 ber after a movement of said transmitting element in either one of two directions and in advance of said release element and means to return into engagement the frictionfaces of both of said elements.

80 30. In mechanism of the character de- scribed a strain inducing member a strain transmitting element, frictionfaces thereon, a release element with like frictionfaces, spring means said release element against 90 said transmitting element and in engagement with said frictionfaces, a strain receiving member engaging said release element means to permanently disengage said release element from said receiving member, if the transmitting power is in excess of the resisting power on said frictionfaces, said release element to disengage from said receiving member after a movement of said transmitting element in either one of two directions and in advance of said release element 95 and means to return into engagement the frictionfaces of both of said elements.

100 31. In mechanism of the character de- scribed a strain inducing member, a strain transmitting element, angular frictionfaces thereon, a release element with like frictionfaces, one or more spring means said release element against said transmitting element and in engagement with said frictionfaces, a strain receiving member engaging said release element, means to permanently dis- 105 engage said release element from said receiving member, if the transmitting power is in excess of the resisting power on said frictionfaces, said release element to disengage from said receiving member after a movement of said transmitting element in either 110 one of two directions and in advance of said release element and means to return into engagement the frictionfaces of both of said elements.

115 32. In mechanism of the character de- scribed a strain inducing member, a strain transmitting element, frictionfaces thereon, a release element with like frictionfaces, pressure means pressing said release element against said transmitting element and in engagement with said frictionfaces, a strain receiving member engaging said re- 120 125 130

lease element, means to permanently disengage said release element from said receiving member if the transmitting power is in excess of the resisting power on said friction faces, said release element to disengage from said receiving member after a movement of said transmitting element in either one of two directions and in advance of said release element and means to return into engagement the frictionfaces of both of said elements.

33. In mechanism of the character described, a strain inducing member, a strain transmitting element fast to said inducing member, a release element, friction faces on both said elements, pressure means to engage the friction faces of said elements, a strain receiving member positively engaging said release element and means to positively release the latter from said receiving member, if the transmitting power is in excess of the resisting power on said friction faces.

34. In mechanism of the character described, a strain inducing member, a strain transmitting element fast to said inducing member, a release element, pressure means to engage under friction said transmitting and release elements, a strain receiving member positively engaging said release element and means to positively release the latter from said receiving member, if the transmitting power is in excess of the resisting friction power on said elements.

35. In mechanism of the character described, a strain inducing member, a strain receiving member, friction means for engagement of both said members, said friction means to positively release said engaged members, if the transmitting power is in excess of the resisting friction power.

Signed at New York city in the county of New York and State of New York this 20th day of May A. D. 1920.

ARTHUR PESTEL.

Certificate of Correction.

It is hereby certified that in Letters Patent No. 1,449,054, granted March 20, 1923, upon the application of Arthur Pestel, of New York, N. Y., for an improvement in "Strain-Releasing Mechanism," errors appear in the printed specification requiring correction as follows: Page 4, line 106, for the word "To" read *Two*; page 5, strike out present lines 67 and 68, claim 1, and insert *a strain receiving member forming a permanent part of said inducing member, a strain*; page 6, lines 100 and 110, claims 16 and 17, after the word "and" insert the word *means*; page 7, line 111, claim 24, for the words "of said element" read *on said element*; and line 115, after the word "against" insert the word *said*; page 8, line 90, claim 30, after the word "means" insert the word *pressing*; same page, strike out present line 108, claim 31, and insert instead *faces, spring means pressing said release*; and that the said Letters Patent should be read with these corrections therein that the same may conform to the record of the case in the Patent Office.

Signed and sealed this 29th day of May, A. D., 1923.

[SEAL.]

KARL FENNING,
Acting Commissioner of Patents.
